TELEPHONE HAND SET

Michel Louis Oules, Velizy, France

Application November 21, 1957, Serial No. 48,582

Claims priority, application France May 22, 1957

Term of patent 14 years

(Cl. D26—14)

FIG. 1

FIG. 2

Fig. 1 is a front perspective view of a telephone hand set, showing my new design with the protective cover for the magneto generator in closed position; and

Fig. 2 is a rear perspective view thereof with the cover in open position.

The broken line fragmentary showing of a connecting cord is for illustrative purposes only.

I claim:

The ornamental design for a telephone hand set, as shown and described.
